UNITED STATES PATENT OFFICE.

WILLIAM C. FISHER, OF MIDDLETOWN, CONNECTICUT, ASSIGNOR TO RUSSELL MANUFACTURING COMPANY, OF MIDDLETOWN, CONNECTICUT.

CONVEYER BELT.

Application filed June 5, 1919. Serial No. 302,009.

To all whom it may concern:

Be it known that I, WILLIAM C. FISHER, a citizen of the United States, and a resident of Middletown, in the county of Middlesex and State of Connecticut, have invented certain new and useful Improvements in Conveyer Belts; and I do hereby declare the following to be a full, clear, and exact description of the invention, such as will enable others skilled in the art to which it appertains to make and use the same.

This invention relates to improvements in conveyer belts and more particularly to such as are adapted to run over idlers arranged in trough formation and employed for conveying material such as coal, grain, and more or less comminuted material, which may be discharged thereon from a chute,—the object of my invention being to provide a woven conveyer belt with a reinforced or thickened central woven portion which shall be capable of effectually withstanding the impact of the load while being deposited thereon and which shall operate to resist the strain to which the central portion of a conveyer belt is subjected during the travel of the same, when loaded, over the idlers of a conveyer mechanism.

With these and other objects in view, the invention consists in certain novel features of construction and combinations of parts as hereinafter set forth and pointed out in the claim.

In the accompanying drawings; Figure 1 is a transverse sectional view illustrating one manner of weaving a conveyer belt embodying my invention; Figure 2 is a sectional view on the line 2—2 of Figure 1, and Figures 3 and 4 are views illustrating other ways of weaving the thickened central portion of the belt.

1, 2, 3, represent the longitudinal or warp threads of the fabric; 4 the weft threads, and 5 the binder threads.

The belt shown in Figures 1 and 2 contains the same number of plies throughout, but for the purpose of thickening and thereby reinforcing the intermediate or central portion 6, the number of warp threads is increased in each ply as indicated at 3, while in the portions 7, 7, between the

thickened central portion 6 and the side portions 8, 8, of the belt, the number of warp threads in each ply is less than in the central portion 6 and greater than in the side portions 8. Thus the belt is gradually thickened from the side portions 8 to the central portion 6 and no shoulders or ledges are formed which would be liable to retain portions of the material and interfere more or less with the satisfactory operation of the conveyer.

Instead of weaving the central portion of the belt by increasing the number of warp threads in this portion of the belt without increasing the number of plies, I may employ larger warp threads 9 as indicated in Figure 3, and the warp threads of the portions 7 between the central portion 6 and the side portions 8, may be sizes intermediate the sizes of the central warp threads 9 and the warp threads 11 of the side portions of the belt.

In the form of the invention shown in Figure 4 the thickened central portion 6 of the belt is formed by increasing the number of plies in this portion of the belt as indicated at 12.

Having fully described my invention what I claim as new and desire to secure by Letters-Patent, is:—

A woven conveyer belt consisting of a plurality of interwoven plies and containing the same number of plies throughout, each ply having a maximum amount of warp thread material in its central portion, a less number of warp threads in its side portions, and a number of warp threads in the portions of the belt between said central portions and side portions which is less than the number of warp threads in said central portion and greater than the number of warp threads in the said side portions.

In testimony whereof, I have signed this specification in the presence of two subscribing witnesses.

WILLIAM C. FISHER.
